US00D675017S

(12) **United States Design Patent**
Van Overbeke

(10) **Patent No.:** **US D675,017 S**
(45) **Date of Patent:** **** Jan. 29, 2013**

(54) **PIECE OF LUGGAGE**

(75) Inventor: **Koert Van Overbeke**, Ghent (BE)

(73) Assignee: **Samsonite IP Holdings S.a.r.l.**,
Luxembourg (LU)

(**) Term: **14 Years**

(21) Appl. No.: **29/414,664**

(22) Filed: **Mar. 1, 2012**

(30) **Foreign Application Priority Data**

Sep. 9, 2011 (EM) 001915059-0001

(51) **LOC (9) Cl.** **03-01**

(52) **U.S. Cl.** **D3/273; D3/276; D3/279; D3/289;**
D3/301

(58) **Field of Classification Search** **D3/273,**
D3/276, 278-279, 283-285, 289, 301; 190/18 A,
190/100-127; 206/278, 286-287.1

See application file for complete search history.
